UNITED STATES PATENT OFFICE.

JACOB J. REITZ, OF AKRON, OHIO, ASSIGNOR OF ONE-FOURTH TO R. DENT McDOWELL,
OF AKRON, OHIO.

PATTERN AND PROCESS FOR MAKING THE SAME.

Application filed May 1, 1925. Serial No. 27,317.

This invention relates to improved patterns and procedure for making the same.

The chief object of the invention is to provide a master match plate pattern of great accuracy and to provide a simple effective method for constructing said patterns in a minimum period of time.

Particularly the invention is directed to the use of a plate of transparent material, such as glass, and to the placement and matching up of the pattern parts on the opposite sides of said plate to produce the required pattern.

The practice of the invention is illustrated in the accompanying drawings and is briefly described below in connection therewith, it being understood, however, that the invention is not limited to the specific procedure or construction illustrated and described.

20 Of the accompanying drawings,

Figure 1 is a plan of a match plate pattern embodying the invention;

Figure 2 is a section on line 2—2 of Figure 1; and

25 Figure 3 is a perspective view of an article made by use of the particular pattern plate shown.

Referring to the drawings, 10 represents a plate of transparent material such as glass which may be laid over a drawing of an arrangement of the parts to be cast and the runs therefor. The half parts 11 and run formers 12 are then adhesively secured on the plate in coincidence with the arrangement on the drawing.

30 The plate 10 is then reversed and half parts 13 are secured thereon in coincidence with the parts 12, whereupon the plate 10 may be used as a master match plate by the use of which cast pieces such as shown in Figure 3 can be produced.

In the practice of the invention a transparent plate of suitable size and shape is laid upon a drawing or blue print of the 45 pattern to be formed and previously made halves of patterns including running gates are applied to the plate so that they are aligned with or coincide with the drawing. These parts are secured on the plate in any 50 suitable way as by the use of an adhesive.

The plate is then reversed and the other half parts are similarly secured to the plate by aligning them with the corresponding

parts visible through the plate. The parts are thus easily and quickly matched and a 55 more accurate pattern results from which the permanent master match plate can be cast.

After the pattern has served its purpose, the parts may be removed from the transparent plate and the latter may be reused 60 for constructing other patterns.

Modifications of the invention may be resorted to without departing from the spirit thereof or the scope of the appended claims. 65

What is claimed is:

1. That method of making match plate patterns which comprises providing a transparent plate, laying the plate over a drawing of the pattern, providing half parts of 70 the various portions of the pattern, applying one set of said parts to the upper side of the plate so as to coincide with the drawing and securing them on said plate with an adhesive, and applying the other set of said 75 half parts to said plate so as to coincide with the corresponding parts of the first set and securing them thereon with an adhesive.

2. That method of making match plate patterns which comprises providing a transparent plate, laying the plate over a drawing of the pattern, providing half parts of the various portions of the pattern, applying one set of said parts to the upper side of the plate so as to coincide with the drawing and securing them on said plate, and applying the other set of said half parts to 80 said plate so as to coincide with the corresponding parts of the first set and securing them thereon.

3. That method of making pattern which comprises providing a transparent plate, applying a half part of a pattern to one side of said plate and securing it thereon, applying a corresponding other half part of 85 the pattern to the other side of said plate by placing it thereon so as to coincide with the first part visible therethrough, and securing said other half part on the plate.

4. A pattern for the purpose described 100 comprising a transparent plate, and corresponding halves of pattern portions adhesively secured in coinciding relation on opposite sides of said plate.

5. A pattern for the purpose described 105 comprising a transparent plate, and corre-

sponding halves of pattern portions secured in coinciding relation on opposite sides of said plate.

6. That method of making patterns which comprises providing a transparent plate, applying a portion of the pattern to one side of the plate and securing it thereon, and

applying another portion of the pattern to the other side of the plate in complementary relation thereto by causing its edges to coincide with the corresponding edges of the first part visible therethrough and securing said other portion on the plate.

JACOB J. REITZ.
